UNITED STATES PATENT OFFICE.

ROYAL NEWTON RIBLET, OF SPOKANE, WASHINGTON.

TRACTION-WHEEL.

1,134,960.

Specification of Letters Patent.

Patented Apr. 6, 1915.

Application filed June 16, 1913. Serial No. 773,932.

To all whom it may concern:

Be it known that I, ROYAL NEWTON RIBLET, a citizen of the United States, residing at Spokane, in the county of Spokane and State of Washington, have invented new and useful Improvements in Traction-Wheels, of which the following is a specification.

My invention relates to improvements in wheels and has as its principal object a wheel which will present an added amount of traction surface to the ground and which may also be fitted onto any vehicle which has previously used a shaft.

A further object of my invention is to design a type of traction wheel which will render the operation of steering easier than when the caterpillar type of driving apparatus is used, and which will, at the same time, present a large tracting surface to the ground.

A third object of my invention is to present a wheel which will adapt itself for the level or grade and strong and durable.

A final object of my invention resides in the particular arrangement and combination of parts hereinafter described.

In the accompanying drawings:—Figure 1 is a side elevation of my improved wheel showing the position which the different parts would take if the wheel was lifted clear of the ground and no weight placed thereon. Fig. 2 is a side elevation showing the position taken immediately upon the wheel touching the ground and the weight being placed on the shaft. This view shows clearly the amount of tracting surface to contact with the ground. Fig. 3 is an elevational view taken from the right or left of Fig. 2. Fig. 4 is a cross section on the line 4—4 of Fig. 1. Fig. 5 is a plan view of one of the parts of my complete wheel. Fig. 6 is a plan view of two of the foot pieces used in my wheel, showing the interior sides thereof and the method of matching the same. Fig. 7 is a perspective view of a modified form of foot piece provided with grousers. Fig. 8 is a perspective view of a foot piece provided with a rubber block. Fig. 9 is a perspective view of the parts shown in Fig. 5.

Throughout the separate views the same part is designated by the same reference character.

Referring more particularly to the drawings, the wheel of the whole is designated by the character 1 and is shown as mounted

on the shaft 2. The wheel 1 comprises two wheel shaped members 3—3, one only of which appears in Figs. 1 and 2, but parts of both of which appear in Fig. 4. The parts 3 in the arrangement shown are rigidly mounted on the shaft 2 and are provided with spokes such as 4 which radiate from the shaft, the outer ends of the spokes being connected by a rim 5. At its point of connection with each of the spokes 4, the rim 5 is perforated to receive pins 6 which extend inwardly from the rim and serve as pivots for crescent shaped rocker arms 7 which are pivoted thereon near their inner edges and half way between the tips. Of course it is immaterial whether the rocker arms 7 pivot on the pins 6 or whether the pins 6 pivot in the rim 5. The rocker arms 7 are perforated at their tips to receive gudgeons 8 by which the rocker arms are pivotally connected to link members 9.

By referring to Fig. 4, it will be seen that there are two sets of the rocker arms 7, one set for each of the wheel members 3, and by referring to Figs. 1 and 2, it will be seen that the rocker arms 7 overlap each other, each alternate rocker arm being placed somewhat farther away from the rim 5 than the others in order to permit of this overlapping arrangement. In order to provide this offset for the rocker arms 7, they are provided with bosses 10. It will be understood that the members 7 are interchangeable but that each alternate member is reversed so as to bring the bosses 10 on the side next to the wheel members 3 in order to space certain of the members 7 from the wheel members in order to permit the overlapping arrangement. The link members 9 extend transversely of the wheel 1, as shown in detail in Figs. 5 and 9. The links 9 are interchangeable but, as clearly shown in Fig. 5, they are not symmetrical. At the end intended to connect with one of the rocker arms 7, each of the link members 9 is provided with two perforated lugs 11 and 12 and it will be seen that the lug 11 is offset from the remainder of the link. At the opposite end from the lugs 11 and 12 the links 9 are provided with three perforated lugs such as 13—13 by which the links 9 are adapted to be connected with foot or tread pieces 14, two of which are shown in detail in Fig. 6. The members 14 are provided with four webs such as 15 which are provided with apertured lugs such as 16 at each end and the

adjacent foot pieces 14 are held together by pins or subshafts 17 which pass through the lugs 16 and which also pass through the apertured lugs 13—13 of two of the links 9.

5 It will be seen from Fig. 6 that the members 14 are interchangeable but that the webs 15 are inclined so that the lugs 16 can overlap without throwing the plates out of alinement. When the adjoining plates 14 10 are thus assembled, as shown in Fig. 6, three spaces such as 18 remain between the four pairs of lugs 16 and it will be understood that the lugs 13 of two of the link members 9 are assembled in the spaces 18 between 15 each pair of bearing plates 14 as clearly indicated in Figs. 1 and 4. It will be understood that on account of the offset portion of the lug 11 on the links 9 that the lugs 13 can be thus assembled side by side by merely 20 reversing the position of one of the links 9 with respect to the other. The relative arrangement of the lugs 16 and 17 is also clearly indicated in Fig. 3.

From the foregoing it will be seen that 25 when the various parts described have been assembled as shown in Fig. 1, the wheel will assume the position shown in that figure unless some weight is placed thereon. When the wheel is placed on the ground and weight 30 placed on the shaft 2 the central wheel members 3 will tend to settle and consequently the pins 6 which happen to be on the lower edge of the rim 5 will be carried downward into the position shown in Fig. 2, carrying 35 with them the corresponding saddle pieces 7, thus bringing the two lower bearing plates 14 into alinement and spreading apart the two central links 9, as clearly shown in this figure. Due to the continuous connection of 40 the various members around the wheel its shape will remain symmetrical, the two hub plates 14 also being brought into alinement as well as the two pairs of plates which lie adjacent to the horizontal diameter of the 45 wheel.

It will be understood that the exterior surfaces such as the plates 14 need not be plain as shown in Fig. 3 but may be provided with 50 projecting strips or grousers 18' as shown in Fig. 7, and preferably extending diagonally of the bearing plates 14', as shown in said figure. In Fig. 8 as shown, still another form of bearing plate 14'' is shown, the outer face of which is recessed as shown 55 at 19 in order to receive a block of resilient material 20 preferably of rubber.

It will be understood that while in the drawings the wheel 1 is shown as being driven by a shaft, a gear train and sprocket 60 and chain may be used as a driving means. It will be understood further that while I have shown and described herein the preferred form of my invention, various modifications thereof may be made without departing 65 from the spirit of my invention, and

that I contemplate all such modifications as are mechanically equivalent of the forms shown and described herein.

Having thus shown and described my invention, what I claim is:—

70 1. A wheel comprising in combination, at least one wheel like member disposed at the side of the traction wheel, rocker arms pivoted to said wheel like members, a set of bearing plates hinged together and describing a figure of greater periphery than said wheel like members, and links connecting said bearing plates and said rocker arms and being pivoted at each end.

75 2. A wheel structure comprising in combination, two wheel like members disposed one on each side of said structure and centrally thereof, rocker arms pivoted to said wheel like members, a bearing surface composed of a continuous series of pivoted bearing plates having its rim greater than the periphery of said wheel like members, and links connecting said bearing plates with said rocker arms, the points of connection between said links and said bearing plates 80 being the same as the point of connection between the bearing plates and the points of connection between the links and the rocker arms being at the ends of the rocker arms.

85 3. A wheel structure comprising in combination, a pair of wheel like members disposed one on each side of the structure, rocker arms pivoted to said wheel like members at the rim thereof and at points centrally situated in said rocker arms, there being two sets of said rocker arms, one set pivoted to each of said wheel like members, the rocker arms in each set being arranged 90 with their ends overlapping, said rocker arms being provided with bosses projecting centrally from one side thereof whereby alternate ones of each set of said rocker arms are spaced from said wheel like members in order to permit said overlapping arrangement 95

100 and being assembled so that each alternate rocker arm is arranged with said lugs presented toward the wheel like member to which the rocker arm is pivoted, a bearing structure comprising a continuous series of pivoted bearing plates, links connected to the opposite ends of said rocker arms and connected also to the points of connection between said plates, there being two of said 105 links pivoted to said bearing surface at each point of connection between the individual bearing plates, and the links connecting to any given point on the bearing structure being connected to adjacent ends of separate rocker arms.

110 4. A wheel structure comprising in combination, a pair of wheel like members disposed one on each side of the structure, crescent shaped rocker arms pivoted to said wheel like members at the 115

rim thereof and at points centrally situated in said crescent shaped members, there being two sets of said crescent shaped members, one set pivoted to each of said wheel like members, the crescent shaped members in each set being arranged with their ends overlapping, said crescent shaped members being provided with bosses projecting centrally from one side thereof whereby alternate ones of each set of said crescent shaped members are spaced from said wheel like members in order to permit said overlapping arrangement and being assembled so that such alternate crescent shaped member is arranged with said lugs presented toward the wheel like member to which the crescent shaped member is pivoted, a bearing structure comprising a continuous series of pivoted bearing plates, links connected to the

opposite ends of said crescent shaped members and connected also to the points of connection between said plates, there being two of said links pivoted to said bearing surface at each point of connection between the individual bearing plates, and the links connecting to any given point on the bearing structure being connected to adjacent ends of alternate rocker arms, and each of said links being connected to two of said crescent shaped members one on each side of the wheel structure. 20
